UNITED STATES PATENT OFFICE.

TAUBE DAVIS, OF NEW YORK, N. Y., ASSIGNOR TO FRANKLIN SIMON & COMPANY, INC.,
OF NEW YORK, N. Y., A CORPORATION OF NEW YORK.

DESIGN FOR A DRESS.

Application filed November 23, 1926. Serial No. 19,823. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the design is distinguished by a band near the lower end of the tunic, presenting a shirring effect except at the front, with a collar member, cuffs, and pocket

agreeing in appearance. The dress is also distinguished by streamers extending down from each end of the collar and a ribbon effect at the front connecting the shirring band.

The figure is a perspective view of a dress, showing my new design, the same being illustrated on a figure.

I claim:

The ornamental design for a dress, substantially as shown and described.

TAUBE DAVIS.
